Howard A. Anderson, Pittsburgh, Pa., assignor to Bissell
Inc., Grand Rapids, Mich., a corporation of Michigan

Filed Mar. 4, 1963, Ser. No. 73,812

Term of patent 14 years

(Cl. D9—2)

FIG. 2 is a rear elevational view thereof;

FIG. 3 is a side elevational view thereof, the side opposite being a mirror image;

FIG. 4 is a top plan view thereof.

Portions are omitted in FIGURE 4 for the convenience of illustration only.

The dominant features of my design reside in the portions shown in full lines.

I claim:

The ornamental design for a carpet cleaner, substantially as shown and described.
